UNITED STATES PATENT OFFICE.

STEPHEN M. BROUGHAM, OF BROOKLYN, ASSIGNOR TO THE STANDARD PENCIL COMPANY, OF NEW YORK COUNTY, NEW YORK.

DROP-MOVEMENT FOR POCKET UTENSILS.

SPECIFICATION forming part of Letters Patent No. 331,941, dated December 8, 1885.

Application filed February 24, 1885. Serial No. 156,812. (No model.)

To all whom it may concern:

Be it known that I, STEPHEN M. BROUGHAM, a citizen of the United States, residing in Brooklyn, in the county of Kings and State of New York, have invented certain new and useful Improvements in Drop-Movements for Pocket Utensils, of which the following is a specification.

This invention relates to "drop-movements," so-called, used chiefly for pocket-pencils, but also applicable to many other articles for the pocket—as pen-knives, button-hooks, pens, tooth-picks, &c. Such drop-movements consist, in general, of the outer tubular casing or body for housing the remaining parts, the "drop," which is a lead-holder or other utensil, arranged to slide into and out of the casing, and a catch or lock attached to the casing and adapted to retain the holder in place when either housed in or protruding from the casing.

Figure 1 of the accompanying drawings is a side elevation of a pocket lead-pencil constructed according to my invention, the outer casing being partly broken away to show the working parts, and the drop or lead-holder being protruded. Fig. 2 is a longitudinal mid-section of the same, the plane of the section being at right angles to that in Fig. 1. Fig. 3 is an inverted mid-section of the pencil, showing the drop or pencil-holder dropped back into the casing. Figs. 4 and 5 are side elevations, on a smaller scale, showing a tooth-pick and button-hook, respectively, constructed according to my invention.

Referring to the drawings, let A designate the usual tubular casing or body portion of the pencil or other pocket utensil; B, the drop or moving part, which slides in the casing, and C the cap or projection at one end of the casing which is depressed to release the drop.

I will first describe the construction shown in Figs. 1, 2, and 3. The pencil-case A consists of an outer tube, *a*, which is contracted or open down at its opposite ends, and an inner tube, *b*, which is fixed to the outer tube at its lower end. The inner tube, *b*, forms the slideway for the drop B, which in this construction constitutes (or carries) the lead-holder of the pencil. This lead-holder, which is of the usual or any ordinary construction, is

clearly shown in Figs. 1 and 2, and requires no description, as it forms no part of my invention. The drop B is extended into the tube *b* a sufficient distance to form a suitable bearing by means of a tube, *c*, which forms a part of the drop, and this tube has a pin, *d*, fixed to it, which works in a longitudinal slot, *e*, in the tube *b*, thereby limiting the lengthwise movement of the drop and keeping it from turning. A long leaf-spring, *f*, which constitutes the locking-spring, is fastened to the outside of the tube *b* by means of a rivet, *g*, at one end. It is provided with two holes, *h*, which coincide with the two extreme positions of the pin *d* at opposite ends of the slot *e*. The spring *f* tends to bow in the middle, or near the lower hole, *h*. Over the spring at its fixed end is placed a ring, *i*, which is pressed against by a spiral spring, *s*, coiled around the tube *b* and within the tube *a*. The upward pressure of this spring tends to force the ring *i* up over the leaf-spring *f*, thereby pressing the latter flat against the tube *b*, as shown in Fig. 2. In this position the pin *d* is confined in one or other of the holes *h*, and the drop is thus locked in place.

The upper end of the case A is closed by the cap or button C, which projects beyond the end of the case, and is made to slide within the contracted end of the tube *a*. This cap is made of a tube, *k*, which fits closely around the outside of the tube *b*, and extends down to and is fastened to the ring *i*. This tube is slotted or cut away down one side, as clearly shown in Fig. 1, to make room for the spring *f*. The cap C, tube *k*, and ring *i* thus all move together, and are pressed upward and the cap protruded by the spring *s*. They are kept from turning by a pin, *l*, fixed in the tube *b*, and working in a slot, *m*, in the tube *k*.

Figs. 1 and 2 show the drop B (or lead-holder) protruded ready for the pencil to be used. It is locked in position by the pin *d* being confined in the lower hole, *h*. To draw the lead-holder, it is necessary to invert the device and press in the cap C, as shown in Fig. 3. This operation presses back the ring *i*, and disengages the locking device by permitting the spring *f* to fly outwardly, thus releasing the pin *d*, whereupon the drop B falls by its own weight into the case A until

the pin *d* is stopped at the opposite end of the slot *e*. This is the position shown in Fig. 3. The drop has just fallen, and the cap *C* is still depressed. On releasing this cap the 5 spring *s* forces up the ring *i* again and crowds the spring *f* against the tube *b*, thus bringing its hole *h* over and confining the pin *d*. The drop *B* will remain thus concealed within the case *A* until the cap *C* is again pressed upon 10 while the pencil is held right side up, when it will again fall out.

Fig. 4 shows on a smaller scale the application of my invention to a gold tooth-pick. It is equally applicable to holders for quill 15 tooth-picks. Fig. 5 shows its application to pocket button-hooks. In both cases the interior mechanism and the operation are the same as already described.

I am aware that drop-movements working 20 with clamping jaws engaging the drop on opposite sides, and operated to release the drop by the pressing in of a longitudinally-movable spring-protruded cap, are not new; and I am also aware that a two ended instrument has 25 been patented, having a pencil at one end and a drop-movement working in the other end, wherein the drop is locked by a spring bearing a pin entering holes at opposite ends of a slot, and is unlocked by an arm which dis- 30 places said pin when the pencil is pressed inward.

I claim as my invention—

1. The combination of a tubular casing, *A*, a drop, *B*, sliding into one end of said casing, 35 a cap, *C*, arranged at the other end thereof, a locking-spring, *f*, for said drop attached to the casing and tending to spring outward away from said drop and release the latter, a locking-slide, *i*, connected to the cap *C*, and adapted 40 to move longitudinally and to engage the locking-spring and press the same inward, and a spring, *g*, acting to force said slide into en-

gagement with said spring, substantially as set forth, whereby the pressing in of said cap acts to disengage said slide from the locking-spring, 45 and thereby to unlock the drop.

2. The combination of a tubular casing, *A*, consisting of outer and inner tubes, drop *B*, sliding into one end of said casing in said inner tube, a cap, *C*, arranged at the other end 50 of said casing, a locking-spring arranged longitudinally in the space between said inner and outer tubes and normally springing outwardly, two locking provisions on said spring at a distance apart equal to the play of the 55 drop and engaging a reciprocal provision on the drop, a slide, *i*, adapted to move longitudinally and to engage the locking-spring and force it inward to lock the drop, tube *k*, connecting said slide *i* to said cap *C*, and a 60 spring, *g*, pressing said slide into engagement with the locking-spring, substantially as set forth.

3. The combination of a tubular casing, *A*, 65 consisting of outer and inner tubes, drop *B*, sliding into one end of said casing in said inner tube, a locking-spring arranged in the space between said outer and inner tubes, and adapted to engage and lock said drop in either extreme position of the latter, a sliding tube, 70 *k*, arranged in the space between said outer and inner tubes with one end extending out at the end of the casing and closed to form a cap, *C*, a disengaging device for the locking-spring connected to said tube, and a spring, 75 *g*, acting to press said tube and cap outward, substantially as set forth.

In witness whereof I have hereunto signed my name in the presence of two subscribing witnesses.

STEPHEN M. BROUGHAM.
